Attorney

Patented Feb. 8, 1927.

UNITED STATES PATENT OFFICE.

THOMAS LUCIEN TALIAFERRO, OF CHICAGO, ILLINOIS.

JAR CLOSURE.

Application filed March 28, 1921. Serial No. 456,303.

The invention relates to new and useful improvements in jar closures, and more particularly to a jar closure for a glass jar having a straight outer side wall.

5 An object of the invention is to provide a jar closure which may be sealed to the jar without reshaping or bending the metal of the closure.

In the drawings—
10 Figure 1 is a sectional view of the upper portion of a jar showing my improved closure as loosely applied thereon;

Figure 2 is a similar view showing the closure as sealed to the jar;

15 Figure 3 is a view similar to Figure 1, but showing a slightly modified form of the depending portion carrying the flange at the outer edge of the closure;

20 Figure 4 is a view similar to Figure 3, but showing the sealing material as sealing the closure on the jar.

In carrying out the invention, I provide a closure preferably of metal, which includes a top portion, a depending portion extending along close to the outer side wall of the jar and an outwardly projecting portion at the lower end thereof and a depending flange at the outer extremity of said outwardly projecting portion. This outwardly projecting portion, together with the depending flange forms a pocket in which is placed a sealing ring which is formed of material capable of being reformed and maintaining its new shape, so that said sealing ring may be reformed after the closure is placed on the receptacle and thus be wedged between the depending flange and the side wall of the receptacle not only sealing the jar but maintaining the closure on 40 the jar.

Referring more in detail to the drawings, my improved jar closure consists of a top portion 1 which is formed into a rounded channel portion 2 adapted to engage over the extreme upper edge of the wall of the jar, which is indicated at 3. Said closure has a depending portion 4, which extends along adjacent the outer wall of the jar and at the lower edge of this depending portion there is an outwardly projecting portion 5 and at the outer extremity of said outwardly projecting portion 5 there is a depending flange 6. This depending flange 6, together with the outwardly projecting portion 5, forms a pocket 7 of substantially

constant shape, in which is placed a sealing ring 8. This sealing ring 8 is preferably made of rubber which has not been vulcanized to any extent, so that the rubber may be molded or reformed and maintain 60 its new shape. The ring may be caused to adhere to the closure and form a part of the closure. This ring 8 in cross section is preferably of greater area than the cross sectional area of the pocket 7 down to a horizontal line at the lower edge of the flange 6.

A closure constructed as noted above is placed on the jar, which may be placed under vacuum, if desired, the closure then pressed down on to the jar and while it is held 70 pressed down on to the jar by a suitable tool or instrument, the packing ring is engaged from below and crowded up into the pocket, as indicated in Figure 2 of the drawings. This crowding of the sealing 75 material into the pocket 7 fills the pocket and causes the material to make close contact with both the inner wall of the projecting portion 5, the inner wall of the flange 6 and the outer wall of the glass jar receptacle. This forms a very efficient seal for the closure for the jar and at the same time, through the adherence of the sealing material to the wall of the jar, holds the closure 80 firmly on the jar.

It will be noted that the jar is closed and sealed without reforming or reshaping the metal in any way. Closures heretofore, so far as I am aware, have all required some reshaping or bending of the metal parts. 90 This is more or less liable to cause a breaking of the glass of the jar, but by my device, where the sealing material alone is reshaped or reformed and the only pressure against the jar is through the more or less elastic 95 sealing material, there is no liability of crushing the jar. The flange 6 is preferably bent outwardly slightly to facilitate the gripping of the sealing material against the side wall of the jar.

100 In the structure shown in Figures 3 and 4, the depending flange 4 of the metal closure is bent outwardly at 9, so as to form a tapered portion 10, into which the pocket 7 leads. The flange 6 also is vertical. Otherwise, the closure is similar in construction to that shown in Figure 1. The sealing material when it is crowded into the pocket 7 is also crowded up into the tapered portion 10 of the pocket and makes a very tight 110

seal at this point in the closure. Otherwise, the structure and the mode of operation are the same.

It is obvious that minor changes in the details of construction may be made without departing from the spirit of the invention, as set forth in the appended claim.

Having thus described my invention, what I claim as new and desire to secure by Letters Patent, is:

A metal closure for jars having a straight side wall, said closure having a depending portion extending along the side wall of the jar and of substantially the same internal diameter as the external diameter of the jar, said depending portion being bent away from the side of the wall of the jar and spaced therefrom so as to form a pocket

of substantially fixed cross section, a sealing ring adapted to be located in said pocket composed of material capable of being re-shaped and maintaining its new shape without being confined by the re-shaping of the pocket containing said sealing material, said sealing ring being of sufficient size so as to initially project below the lower edge of the closure whereby said ring may be engaged by suitable tools for pressing the sealing ring into the pocket and re-shaping the same therein so as to cause said ring to firmly contact with the inner walls of the pocket and the wall of the jar adjacent the pocket for sealing the closure on the jar.

In testimony whereof, I affix my signature.

THOMAS LUCIEN TALIAFERRO.
